UNITED STATES PATENT OFFICE

JOSEPH O. CADIEUX, OF MERIDEN, CONNECTICUT, ASSIGNOR TO CONNECTICUT TELEPHONE & ELECTRIC CORPORATION, OF MERIDEN, CONNECTICUT, A CORPORATION OF DELAWARE

TELEPHONE

Application filed June 7, 1930. Serial No. 459,807.

My invention relates particularly to what are sometimes termed apartment house telephones.

One object is to provide a construction which can be readily installed and wired.

Another object is to provide a construction which is compact and yet capable of connection and use in a variety of different ways.

Another object is to provide a construction of the character described which can be economically made and assembled.

Another object is to provide a construction of the above character which can be readily plugged into and removed from wall connections without the use of binding posts, screws, or the like.

Another object is to provide a construction which is particularly adapted for embodiment in a metal casing.

In the preferred form the apparatus comprises a casing or housing composed of two parts, namely, a wall or supporting back member and a front or detachable body member. The back member carries a series of stationary jaws or sockets which are electrically connected to the house wiring system, and the front member carries the transmitter, the bell, the push buttons, the receiver switch and all the necessary connections, together with blades adapted to be plugged into the sockets.

In the form herein shown the casing consists of a body portion adapted to be mounted upon or embedded in a wall and a front plate carrying an insulating block with the transmitter, receiver, bell and push button connections and plug blades adapted to be inserted into corresponding sockets supported in the body of the casing.

The invention is broadly claimed by my Patent #1,717,091.

Fig. 1 is a front view of the main body of the casing with the circuit terminals and plug in sockets.

Fig. 2 is a rear view of the front plate with its attached parts.

Fig. 3 is a horizontal section and end view of the assembled parts of the apparatus, but looking upwardly.

Fig. 4 is a fragmentary vertical sectional

view of the assembled parts showing the plug in contacts in engagement with each other.

Fig. 5 is a side view and partial vertical section of a modification of the invention.

Fig. 6 is a front view and section of the construction shown in Fig. 5, the section being taken on the plane of the line 6—6 of Fig. 5.

The body of the receptacle or casing 10 may be of steel or other suitable material 60 and has a cover portion 11 which may be secured in place by screws 12 passing through keyhole openings 13 into the body of the casing.

The front plate or wall plate 14 may be of suitable material such as sheet metal of suitable design and adapted to be secured in place by screws 15 which pass through the front plate into the screw seats 16 in the lugs 17.

The insulating block 18 is suitably secured to the back of the front plate 14 and provided with recesses 19 corresponding with the lugs 17 so as to serve as alining means for properly positioning the front plate and attached parts 75 with respect to the wall box.

One or more signal bells 20 are preferably provided and mounted upon the front plate and adapted to be actuated by suitable electro-magnetic devices 21 of the usual character.

A transmitter may be of any suitable character as for instance the microphone 22 with a diaphragm 23 and mouth piece 24 supported within the front plate 14.

The receiver 25 may be of any suitable type and adapted to be hung on the hook 26 of a suitable switch 27, the latter being secured to the rear of the insulating block 18 in any suitable manner. The construction of the transmitter and receiver may be embodied in a combination hand instrument as is customary in telephone construction and adapted to be suspended from the hook 26 and actuate the switch 27 in the usual manner.

Constructions of this character are usually provided with one or more push button switches for signaling the janitor, releasing the front door catch of the apartment, etc.

Such a switch would have a stationary con-

tact 30 and a spring finger contact member 31 secured for instance by a screw 32 at the rear of the insulating block 18. Such a switch may be conveniently operated by the push 5 button 33 which slides through the block 18 on the front plate 14. The plate 34 serves as an anchorage for the screw 32.

To the back of the insulating block 18 are secured a number of blades 35 electrically 10 connected to the respective parts of the transmitter, receiver, bell and push buttons. A convenient method of supporting these blades is shown in Fig. 4 where the blade 35 is secured by a tubular rivet 36 to the plate 34.

15 An insulating block 37 mounted within the wall body or box of the casing may be supported by hangers 38 which are secured by screws 39. Upon this block 37 is mounted a series of spring sockets 41 corresponding with 20 the plug-in blades 35. Each of these sockets has one or more spring jaws for appropriate yielding and sliding connection with the blades and is secured in place for instance by the screw 42. Each of these sockets 41 has 25 a terminal plate 43 and binding screw 44 for attachment of the conductors which are led into the box 10 in any suitable manner.

The various parts of the transmitter, receiver, etc. are, as above stated, connected to 30 the respective plug-in blades 35 so that they can all be plugged-in to the wall sockets simultaneously for convenience in installation and so that the wall plate and attached instrument parts may be readily removed 35 when desired.

In the construction shown in Figs. 5 and 6 the casing 50 is more particularly intended to be mounted on the outside of the wall and contains an insulating block 51 with terminal 40 sockets 52.

The front plate 53 carries an insulating block 54 on which the various instruments are mounted such as the bell 55, the transmitter 56, the hook switch 57 and receiver 45 hook 58 and push button switch 59. This block 54 also carries a row of plug-in blades 60 connected to the respective electrical instruments and adapted to engage the apparatus contact jaws 52 which are mounted in 50 the body of the casing 50.

It will be seen from the foregoing that in each form of the invention herein illustrated the wall box can be installed and wired into the house line very readily, even before the 55 face plate or the transmitter and receiver, etc. are available. After the wiring in the house and connections through the sockets such as 41 and 52 are completed, the front part of the casing with the attached instruments is 60 readily inserted and secured in place without necessitating any of the usual wiring to be done.

I claim:

1. In a telephone instrument, a box adapted to be secured to a wall, an insulating sup-

port carried thereby, circuit terminals on said support, a front plate detachably connected to the box, an insulating block carried by the plate and projecting rearwardly therefrom, a hook switch carried by said insulating block, a transmitter and a receiver connected to the hook switch, and automatically engaging contacts carried by said insulating support and said block and connected to said transmitter, receiver and hook switch. 75

2. In a telephone, a casing having a box and a front plate, circuit terminals mounted in said box, the front plate being detachably connected to the box and having transmitter, receiver and hook switch connections and 80 automatically engaging contacts carried by said plate and box and connected respectively to said transmitter, receiver and hook switch.

3. A telephone instrument comprising a box 85 having a series of terminals and contacts, a front plate, an insulating block carried thereby and having contacts adapted to said other contacts, a transmitter and receiver connected to said block, said box and said block having interfitting aligning members coacting with 90 each other during the connection of the contacts.

4. A telephone instrument comprising a wall box having a series of contacts, a front 95 insulating body having contacts adapted to the other contacts, a transmitter and receiver carried by the insulating body, said box and said body having interfitting aligning flanges and grooves coacting with each other in advance of the connection of the contacts.

5. A telephone instrument comprising a box member having a row of contacts, a front member having contacts adapted to said box member contacts, a transmitter and a receiver, a switch carried by the front member and connected to the transmitter and receiver, said box member and said front member having interfitting aligning members coacting with each other during the connection of the contacts and means for securing the front and box members together. 105

6. A telephone instrument comprising a box having a series of sockets, a front plate and insulating body having contacts adapted to fit in said sockets, a transmitter and receiver having terminals carried by the insulating body, said box and said body having interfitting aligning members coacting with each other in advance of the insertion of the contacts into the sockets. 110

7. A telephone comprising a box having a series of sockets, a front plate and insulating block having contacts adapted to said sockets, a bell, push buttons, a transmitter and having receiver terminals carried by the block, said box and said block having interfitting aligning members coacting with each other during the insertion of the contacts 115 120 125 130

into the sockets and means for securing the plate and box together.

8. In a telephone instrument, a box adapted to be secured to a wall, an insulating block carried thereby, circuit terminals on said block, a front plate detachably connected to the box and having an insulating block, a signal bell, a transmitter, a receiver and a hook switch having terminals carried by said insulating block on said plate and automatically engaging contacts carried by said insulating blocks and connected respectively to said bell transmitter, receiver and hook switch.
